PARASITICIDE

Lewis W. Butz, Chalfont, Pa., assignor to Dr. D. Jayne & Son, Inc., Wilmington, Del., a corporation of Delaware

No Drawing. Application June 13, 1935,
Serial No. 26,521

1 Claim. (Cl. 167—65)

This invention relates to parasiticides, more particularly to new and improved compositions adapted to effect the removal of internal animal parasites from host animals, including man.

5 "Animal parasites" is here defined as all parasitic organisms exclusive of plants and bacteria.

It is known that amebas, worms and other protozoa and metazoa infest the gastro-intestinal tract as well as other sites in the body. Numerous preparations designed to kill or eliminate such parasites have been proposed, these being known as amebicides, anthelmintics, or in general, parasiticides. A number of such preparations have met with success, but they have been

15 highly specific in their action in the sense that only a limited group or even only one species in a group of parasites is affected. Moreover most of these have been shown to be highly toxic to the host. Probably two of the best known remedies heretofore used are oil of Chenopodium (active component, ascaridole) and tetrachlorethylene.

The term vermicide is used in the claims to designate the compositions and the remedial effects contemplated by this invention and referred to in this application. The term vermicide is used in its accepted meaning and can be defined as an anthelmintic drug or medicine destructive to intestinal animal parasites. Such 20 parasites, specifically, are those referred to above and include but are not limited to those mentioned specifically in the description of this application.

With a view to advancing the development of the art of parasiticides, researches have been conducted resulting in the inventions and discoveries set forth in the following specification.

It is an object of the invention to provide new and improved antiparasitic compounds. One improvement in view is that new remedies shall be less specific in their application than those hitherto proposed. Since the parasites envisaged in this invention exist in environments practically free of oxygen and are harmfully affected by oxygen in certain active forms, the desired generality of the drug effect is aimed to be accomplished by the application of remedies supplying oxygen in suitable form and amount. The invention, then, has for its further objects the use 45 of new and improved antiparasitic compounds containing oxygen in such suitable form, and particularly organic peroxides. Further objects are specifically included in the particular compounds set forth in this specification.

50 The compounds found to be particularly useful

according to the present invention are organic peroxides, which term is to be understood to include derivatives of hydrocarbons containing the peroxide (—O₂) group, which derivatives may in addition contain other substituent groups or elements commonly found in organic compounds, such as hydroxyl (—OH), iodine (—I), carboxyl (—CO₂H), oxide (—O—), etc.

The use of oil of Chenopodium has been established as an efficient antiparasitic remedy in infestations of human beings and lower animals. The remedial effect of this oil has been shown to be due to the organic peroxide, ascaridole, which it contains.

It is probable that the therapeutic effect of ascaridole is due, in part at least, to the peroxide group which it contains. This compound however contains other important groupings; namely, the olefin linkage and the para-menthene structure. Possibly because of these latter structural units this peroxide is quite toxic for human beings and lower animals. The use of Chenopodium oil is unsafe in view of its high toxicity when administered in doses sufficiently large and frequent to produce its anti-parasitic effect. This invention has for one of its objects the therapeutic use of organic peroxides, as above described, with much reduced toxicity for the host. This can be obtained by the preparation and bioassay of many peroxide compounds with or without substituent groups. I have studied some other peroxides as anthelmintics and have found 30 these to be superior therapeutic agents.

As an approach to the solution of this question, the action of hydrogen peroxide and of disuccinyl peroxide has been studied, with particular reference to *Ascaris lumbricoides*, and these substances have been found to be very toxic to the parasites. (J. Am. Pharm. Assn. vol. XXIII, #11, November 1934). This indicates that the peroxide group, or the hydrogen peroxide or nascent oxygen therefrom under various conditions, has in itself pronounced anthelmintic properties. In view of these findings, researches have been extended to the utilization of other peroxides with a view to finding those that have the desired property of low toxicity for the human 40 45 50 55

host, and in addition sufficient stability to serve as therapeutic agents. Organic synthetic methods can supply a very large variety of organic peroxides exhibiting all degrees of stability and physical properties such as solubility in water. 5 Rieche (Alkyl-peroxide v. Ozonide 1931) has described the preparation and properties of some of these, and I have studied the action of one, described by Rieche, upon *Ascaris lumbricoides* in beaker tests and upon *Toxocara canis* in dogs. 10 This compound, diheptanol peroxide, has the probable structural formula,

15 It was found that diheptanol peroxide killed *Ascaris lumbricoides* readily in the beaker and that dogs were freed of all *Toxocara canis* which they had harbored by treatment with this peroxide. 20 By assaying diheptanol peroxide for antihelmintic efficiency and toxicity for the host upon a large number of dogs and conducting simultaneously the same experiments with Chenopodium oil, we have shown that the ratio of 25 antihelmintic efficiency to toxicity is much higher for diheptanol peroxide than for Chenopodium oil, and therefore that diheptanol peroxide is a better drug for this parasitic disease, ascariasis. And yet it must be emphasized that in all probability further search among synthetic organic 30 peroxides will reveal compounds with remedial properties even superior to those of diheptanol peroxide.

35 A typical example of a bioassay with *Ascaris lumbricoides* is as follows:

Bioassay

The effect of the antihelmintic activity toward 40 *Ascaris lumbricoides* was determined by immersion of vigorous specimens in a solution or emulsion of the substance being tested. The apparatus was a rectangular aquarium with glass windows which was filled with water and served as a constant temperature bath. The temperature 45 was maintained between 37° C. and 38° C. The aquarium was provided with a metal cover con-

worms were 22-24 cm. in length and weighed 2.0-2.35 gms. They were *A. lumbricoides* obtained from the intestines of swine. Observation was made of the number of minutes after immersion required to produce cessation of movement, paralysis and death and were conducted at hourly intervals for a period of five hours.

5 In general, it is found that organic compounds containing a peroxide group are effective as antihelmintics in the beaker tests described. These 10 tests have shown that hydrogen peroxide, disuccinyl peroxide, diheptanol peroxide were all very toxic to the round worm, *Ascaris lumbricoides*. In using the term "peroxide group" it is to be understood that this includes substances 15 containing the —O—O— linkage or tautomeric modifications thereof. A general formula for such a composition would be $\text{R}_1\text{O}.\text{OR}_2$ where 20 R_1, R_2 are either hydrogen or a hydrocarbon radical or a derivative thereof. In addition to antiparasitic effect the therapeutic peroxide must have sufficient chemical stability to reach the site of infestation and to remain there for a sufficient period to exert the antiparasitic action. This requirement renders hydrogen peroxide and some 25 organic peroxides such as some of those containing the

30 and

35 linkages unsuitable because these decompose too readily in the presence of water and body fluids. For the therapeutic experiments, therefore, I chose diheptanol peroxide since this has a high degree of stability as shown by its passage through the gastrointestinal tract of dogs little altered in shape or amount while at the same time ridding 40 the dog of all the worms present. Diheptanol peroxide is, therefore, included here as an example of a suitable therapeutic compound.

45 Therapeutic experiments with reference to diheptanol peroxide show the following results in canine ascariasis:

TABLE I

Percentage of worms removed

Drug	Dose	No. of animals	Worms present	Worms removed	Percent removed
	(g./kg.)				
Diheptanol peroxide.....	0.2	6	129	48	37
Do.....	0.3	2	25	22	88
Do.....	1.0	8	138	128	93

TABLE II

Rate of elimination of worms before and after treatment with diheptanol peroxide

Dog No.	Dose	Cure	Rate eliminated (worms/day)		No. of worms eliminated		
	(g./kg.)	(Percent)	Before	After	Before	After	Autopsy
161.....	1.02	100.0	0.2	14.0	1	14	0
59.....	0.30	100.0	0.2	13.0	2	17	0

65 taining holes which supported 400 cc. beakers. Five worms were placed in each beaker which 70 contained 300 cc. of solution or emulsion. The

70 Diheptanol peroxide was administered in solid form in gelatin capsules. The animals were observed for periods of seven to ten days prior to 75

treatment and the rate of elimination of worms observed over this period. After treatment they were observed for varying periods of time and then sacrificed. The number of worms passed during life and found at autopsy were observed. The two tables above show (1) the percentage of total worms present eliminated by the treatment as observed with a large number of dogs, and (2) the difference in rate of elimination of parasites before and after treatment. All experiments carried out consisted of one dose treatments, the diheptanol peroxide being given without solvents and without any other medicaments such as laxatives.

Experiments have been conducted to assure that effective doses of diheptanol peroxide can be tolerated by the infested animals. The therapeutic dosage of diheptanol peroxide was found to be between 0.3 and 1.0 g./kg. and laboratory data revealed that from 15 to 5 times this dosage respectively was easily tolerated by the dog. In fact, toxic effects from this material upon the host have never been observed and therefore a maximum tolerated dose cannot be stated at this time. Higher doses were not given because of

the mechanical difficulties involved in administering such quantities with a one-dose technique. However, one dog showed no symptoms of intoxication on receiving five doses of 3.0 g./kg. each at short intervals. Moreover it is 5 likely that the administration of diheptanol peroxide in a suitable solvent would show that less than the dose rate of 0.3-1.0 g./kg. would be therapeutically effective. These results show the suitability and safety of diheptanol peroxide 10 as a drug and hence indicate its superiority to Chenopodium oil. The therapeutic index (rate of maximum tolerated dose to minimum therapeutic dose) in dogs was found to be 8.0 for Chenopodium oil, while the above data show that 15 this index for diheptanol peroxide is at least 15.0 and is probably much higher.

Having thus described the invention and the therapeutic application thereof, I claim:

A vermicide adapted for internal administration, comprising diheptanol peroxide
